UNITED STATES PATENT OFFICE.

ESTELL M. HIXSON, OF NAMPA, IDAHO.

TOOL BOX.

Application filed August 27, 1926. Serial No. 131,983.

This invention relates to a tool box, the general object of the invention being to provide a plurality of trays in the box, with means for adjusting the trays by the raising of the lid of the box to a position where the contents of all the trays will be accessible, the trays moving to a position where the lid can be closed to cover them, upon the closing of the lid.

10 Another object of the invention is to provide means for moving one of the trays outwardly beyond the front of the box so that articles in the lower part of the box will be accessible.

15 This invention also consists in certain other features of construction and in the combination and arrangement of the several parts, to be hereinafter fully described, illustrated in the accompanying drawings and 20 specifically pointed out in the appended claim.

25 In describing my invention in detail, reference will be had to the accompanying drawings wherein like characters denote like or corresponding parts throughout the several views, and in which:—

Figure 1 is a front view of the box in closed position.

Figure 2 is a perspective view with the 30 box in open position.

Figure 3 is a transverse sectional view similar to Figure 4 but shows the box in open position.

Figure 4 is a section on line 4—4 of Figure 1 with parts broken away.

Figure 5 is a section on line 5—5 of Figure 3.

Figure 6 is a sectional view on line 6—6 of Figure 3.

40 Figure 7 is a section on line 7—7 of Figure 2.

Figure 8 is a section on line 8—8 of Figure 5.

Figure 9 is a section on line 9—9 of Figure 3.

45 In these views, 10 indicates the body of the box and 11 indicates the lid thereof which is provided with a flange 12 at its rear which is connected by the hinges 13 to a flange 14 at the rear of the body. The front of the box is cut away, as at 15, and it is provided with tubular flanges 16 at the top of its end parts, the flanges being of square shape in cross section. The lid is 55 provided with end flanges 17 for enclosing the flanges 16. Short track forming strips

18 extend horizontally from the rear of the box for slidably supporting a tray 19 which is provided with the angle pieces 20 on its bottom which engage the inner edges 60 of the strips 18 to prevent endwise movement of the tray. Angle pieces 21 extend from the front to the rear of the box adjacent each end thereof with their lower flanges flush with the upper edge of the front of the 65 box, these strips forming tracks for a front tray 22 which has angle pieces 23 secured to the lower corners of its ends and these pieces rest upon the track forming pieces 21. A loop 24, formed of a metal strip fastened 70 to the inner end of each piece 23, encircles the pieces 21 and 23 so as to slidably connect each piece 23 with the track piece 21. Each loop 24 is provided with a projection 25 which engages the slotted upper end of a 75 lever 26 which is pivoted at its lower end to each end of the box. When the tray 22 is in its innermost position, its front wall will close the opening formed by the cut-away portion 15 and said front wall is provided with the end extensions 27 for closing the member 16.

80 A second lever 28 is pivoted intermediate its ends to each end of the box and the lower end of each lever 28 is connected 85 with the lever 26 by a link 29. A lever 30 is pivoted at one of its ends to a bracket 31 at each end of the lid, at the rear thereof and the front end of each lever 30 is pivoted to the upper end of each lever 28. Thus 90 when the lid is opened, the levers 28 will be rocked through means of the levers 30, and this movement will be communicated to the levers 26 by the links 29 so that said levers 26 will be tilted forwardly so as to 95 move the tray 22 outwardly, as shown in Figures 2 and 3, by the forked ends being connected with the loops 24, through means of the projections 25. As the lid is lowered, the parts will be moved in an opposite 100 direction so that the tray 22 will be moved inwardly until its front engages the front of the box. In this position, the front of the lid will overlap the top part of the front of the tray so that the parts will be completely closed. The box can be locked through means of the hasp 32 on the lid and the staple 33 on the tray.

105 A tray 34 is hinged to the rear of the lid by the hinges 35 and a tray 36 is hinged 110 to the lid by the hinges 37. The two trays are connected together by the links 38 which

- 25
- are pivoted to the ends of the trays. A bar 39 is pivoted to each end of the tray 36 and has its lower bent end passing through a slot 40 formed in each flange 16 and this end of each bar 39 is pivotally connected with the flange by a pin 41. Thus as the lid is moved to open position, the bars 39 will move the tray 36 to open position and as this tray is connected with 10 the tray 34 by the links 38, this tray 34 will also be moved to open position. As the lid is closed, the bars 39 will cause the trays 36 and 34 to swing back into the lid into closed position, as shown in Figure 4.
- 15 I prefer to make the tray 34 with its front open and its bottom provided with an upwardly and outwardly extending extension 42 so that this tray can be used as a saw rack.
- 20 From the foregoing, it will be seen that I have provided a tool box whereby all the trays will be moved to a position by the opening of the lid, where their contents are readily accessible with a space between the 25 trays 19 and 22 so that the bottom of the box is accessible. When desired, the tray 19 can be moved forwardly, so that the tray 34 will not interfere with the removal of objects from said tray 19.
- 30 With this box, the entire interior space is made use of and the various tools or

other objects can be taken from the different compartments or placed therein without removing other articles as is the case where the tools are all piled together in one compartment or in compartments placed one upon the other. 35

It is thought from the foregoing description that the advantages and novel features of my invention will be readily apparent. 40

I desire it to be understood that I may make changes in the construction and in the combination and arrangement of the several parts, provided that such changes fall within the scope of the appended claim. 45

What I claim is:—

A box of the class described comprising a body, a lid hinged thereto, a tray slidably mounted in the front of the box, means actuated by the opening of the lid for moving 50 the tray outwardly, a second tray in the body, a track for slidably supporting the second tray, a pair of trays hinged in the lid, links pivotally connected with the trays in the lid for causing the trays to move 55 in unison and a rod pivotally connected with one of said trays in the lid and with a part of the body for swinging the trays in the lid to open position when the lid is moved to open position. 60

In testimony whereof I affix my signature.

ESTELL M. HIXSON.
